RADIO CABINET

Robert W. Becker, Naperville, and Melvin H. Boldt,
Glenview, Ill., assignors to Zenith Radio Corporation,
Chicago, Ill., a corporation of Delaware

Filed May 27, 1969, Ser. No. 17,367

Term of patent 14 years

Int. Cl. D14—03

U.S. Cl. D56—4

FIG. 1

FIG. 2

FIG. 3

FIG. 4

FIG. 1 is a front elevational view of our design for a radio cabinet;

FIG. 2 is a top plan view thereof;

FIG. 3 is a side view thereof; and

FIG. 4 is a rear perspective view showing the top, side and rear thereof.

Portions of the drawing figures are diagonally lined to indicate transparency, and portions are shaded to indicate contrast in appearance.

We claim:

The ornamental design for a radio cabinet, substantially as shown and described.
